Design No. 2,960, dated March 24, 1868.

DESIGN FOR A BOTTLE.

The Schedule referred to in these Letters Patent and making part of the same.

TO ALL WHOM IT MAY CONCERN:

Be it known that I, MEIGS JACKSON, of the town of Clarksburg, in the county of Harrison, and State of West Virginia, have originated and designed a New Pattern for a Bottle, and also a design for a trade-mark, of which the following is a full, clear, and exact description, reference being had to the accompanying trade-mark, making part of this specification.

Bottle in form and shape of a Chinaman; neck of the bottle coming up out of the head of the figure; cape falling down over the shoulders of the man figure; long moustache; long queue from the back of the head; cap on head; indentation on front and back of bottle for label. Blown in the bottle the letters "R. S. Gardner & Co., Proprietors, Clarksburg, W. Va."

The said trade-mark, which I have designed, and which will be printed on a label of a size sufficient to fill the indentation in the front of the bottle, is in the words and figures following, to wit:

What I claim as my invention, and desire to secure by Letters Patent, is—
The design for a bottle, as herein set forth and shown.

MEIGS JACKSON.
